F. A. ROCKWELL

PIN BALL GAME DEVICE

Filed Feb. 26, 1927

UNITED STATES PATENT OFFICE.

FOREST A. ROCKWELL, OF DETROIT, MICHIGAN.

PIN-BALL GAME DEVICE.

Application filed February 26, 1927. Serial No. 171,163.

My invention relates to a new and useful improvement in a pin ball game device which may be used as a parlor game, or which may be used in amusement places, such as bowling alleys, billiard halls, and the like.

In this invention there is provided a platform or floor, projecting upwardly from which are a number of pins which, when struck by a ball thrown by the player, will be rocked on their pivots so as to move into horizontal or inclined position, the construction being such that when moved to inclined position, they will disappear below the upper surface of the floor over which the ball is rolled. The game is constructed to closely resemble the game of bowling, and since in the game of bowling there is possible a certain scoring known as a strike and a spare, in this device it is also desirable that such a scoring may be made in order to add to the attractiveness of the game, and increase its popularity.

It is an object of the present invention to provide a structure wherein, upon striking one of the pins and moving it to inclined position, a mechanism will be released for moving all of the other pins to inclined position.

Another object of the invention is the provision of a plurality of pins pivotally mounted and so constructed and arranged that they may be simultaneously moved to upright or operative position.

Another object of the invention is the provision of a device of this class whereby, upon an adjustment of a single part, the release of the master pin will not affect in any manner the movement of the other pins.

Another object of the invention is the provision of a device of this class which is simple in structure, economical of manufacture, highly efficient in use, and of such a compact structure that it may be easily moved from place to place.

Other objects will appear hereinafter.

The invention consists in the combination and arrangement of parts hereinafter described and claimed.

The invention will be best understood by a reference to the accompanying drawings which form a part of this specification and in which,

Fig. 1 is a top plan view of the invention with a part broken away.

Fig. 2 is a sectional view taken on line 2—2 of Fig. 1.

Fig. 3 is a sectional view taken on line 3—3 of Fig. 2.

Fig. 4 is a view taken on line 4—4 of Fig. 2.

Fig. 5 is a fragmentary enlarged sectional view illustrating the locking dog used in the invention.

As shown in the drawings, there is provided a base 7 supported at one end by the swingably mounted support 8 and at the other end by the support 9. Projecting upwardly from the rear end of the base 7 is a rear wall 10 and adjacent the forward end is the forward wall 11. Supported by the forward wall 11 and the side walls 13 and 14 is a floor 12 at opposite sides formed of thinner material than at the center to provide gutters or alley ways 15 and 16, for the reception of the balls used in the game. A pad 18 is mounted on the inner surface of the rear wall 10 at the upper side thereof, to form an impact member for the balls which are used in the game. Projecting inwardly from the rear wall 10 is a shelf forming member 17 which extends forwardly from the rear wall 10 a greater distance than does the shelf 19 which serves partially as a support for the rear end of the floor 12.

Mounted on the side walls 13 and 14 and projecting outwardly therefrom are supporting clips 20, 21, 22 and 23 which serve to engage the undersurface of and support a slidable plate or board 24 in which are formed openings 25 adapted to register with openings 27 formed in the floor 12. Mounted at opposite ends in the side walls 13 and 14 are rods 28, upon each of which is mounted a plurality of pins 29, which project through one of the openings 25 so, when raised to upright position, extend above the surface of the floor 12 engaging in the openings or slots 27. Mounted at opposite ends in the side walls 13 and 14 is a rod 30 upon which is pivotally mounted the pin 31 which projects upwardly when in upright position through one of the openings 25 and a registering opening 27. Mounted on the block 32 is a dog 33 which extends through the

slot 26 formed in the pin 31 at one end, and is adapted to engage at the opposite end an abutment block 34 which is fixedly mounted on the plate 24, this plate 24 being slidable 5 longitudinally of the floor 12. The dog is so mounted, intermediate its ends, that it will, by gravity, assume a position where the nose of the dog is engaging the block 34. Attached to the rearward end of the slid- 10 able plate 24 is a cord 35 which carries at its free end a weight 36, this cord passing over a pulley 43 which is mounted in the bracket 44 suspended from the shelf 19. Attached to the forward end of the slidable 15 plate 24 is a cord 37 which extends to the forward end of the section 38 which is attached to the main body.

In operation the plate 24 is moved forwardly by the cord 37 so as to bring the pins 20 into upright position, as shown in Fig. 2. The dog will then engage the block 34 and prevent the weight 36 from moving the plate 24 rearwardly. The player will then roll 25 the balls upwardly on the floor 12 so as to knock the pins struck on their pivot into inclined position, as shown in dotted lines in Fig. 2. The ball, after striking the pad 18 will strike the shelf 19 from which it may roll to either side and return by either 30 the gutter 16 or the gutter 15. When the pin 31 is struck and moved to inclined position, on account of the projection of the dog through the slot 26, the dog will also be 35 rocked in position shown in dotted lines in Fig. 5, and the plate 24 released for slidable movement rearwardly in response to the pressure exerted by the weight 36, thus causing all of the pins to be moved to inclined position.

40 It is evident, therefore, that if the pin 31 is struck with the first ball, that the equivalent of a "strike" in a bowling game is scored, and that if the pin 31 is struck and knocked to inclined position by a subse- 45 quently thrown ball, the equivalent of a "spare" is scored.

If it is desired to prevent the plate 24 from moving all of the pins to inclined position, the movable abutment strip 39, from 50 which projects an operating handle 40 through the side wall 13, may be moved rearwardly to rest beneath the weight 36, so that when the pin 31 is moved to disengage 55 the dog from the block 34, the weight 36 will rest upon the strip or abutment 39, and the plate 24 moved but slightly rearwardly and a less distance than is necessary to move all of the pins to inclined position.

60 In this manner, I have provided a device where a game of ten pins may be played, closely simulating the bowling game as now played on permanent bowling alleys. It is believed that the simplicity of the structure is apparent, as well as its durability.

65 While I have illustrated and described the

preferred form of construction, I do not wish to limit myself to the precise details of structure shown, but desire to avail myself of such variations and modifications as come within the scope of the appended claims. 70

Having thus described my invention what I claim as new and desire to secure by Letters Patent is:

1. A pin ball game device of the class described comprising: a floor; a plurality of pivotally mounted pins projecting upwardly from said floor and adapted upon engagement with a ball rolled on said floor for being moved out of upwardly projected position; a slide; means for moving said slide, the movement of said slide in one direction a predetermined distance effecting the movement of all of said pins out of upwardly projected position; means for locking said slide against movement; means for moving said slide upon release of said locking means, one of said pins upon movement out of upwardly projected position effecting a release of said locking means. 75

2. A pin ball game device of the class described, comprising: a floor having a plurality of openings formed therein; a plurality of pivotally mounted pins projecting upwardly through said openings; a slide adapted upon movement in one direction a predetermined distance for moving said pins out of upwardly projected position, and adapted upon movement in the other direction for raising said pins to upwardly projected position; means for locking said slide against movement; means for moving said slide upon release of said locking means, one of said pins upon movement out of upwardly projected position effecting a release of said locking means; and means for moving said slide in a direction to raise said pins to upwardly projected position. 100

3. A pin ball game device of the class described comprising: a floor; a plurality of pivotally mounted pins projecting upwardly from said floor and adapted upon engagement with a ball rolled on said floor for being moved out of upwardly projected position; a slide; means for moving said slide, the movement of said slide in one direction a predetermined distance effecting the movement of all of said pins out of upwardly projected position; means for locking said slide against movement; means for moving said slide upon release of said locking means, one of said pins upon movement out of upwardly projected position effecting a release of said locking means; and means for preventing movement of said slide in one direction sufficiently to move said pins to downwardly inclined position upon release of said locking means. 110

4. A pin ball game device of the class described comprising: a floor having a plurality of openings formed therein; a slide posi- 120

tioned below said floor and provided with a plurality of openings formed therein in alignment with the openings in said floor; a plurality of pins pivotally mounted below said slide and projecting upwardly through said openings and extending above said floor, said pins being adapted for movement to downwardly inclined position upon engagement with a ball rolled on said floor; 5 means for locking said slide against movement in one direction, the movement of said slide in one direction a predetermined distance, moving all of said pins to downwardly inclined position, one of said pins upon 10 movement to downwardly inclined position effecting a release of said locking means; means, operable at will, for preventing a movement of said slide in said direction, upon release of said locking means, a sufficient distance to move said pins to downwardly inclined position. 15 5. A pin ball game device of the class described, comprising: a floor having a plurality of openings formed therein; a slide positioned below said floor and provided with a plurality of openings formed therein 20 in alignment with the openings in said floor; a plurality of pins pivotally mounted below said slide and projecting upwardly through said openings and extending above said floor, said pins being adapted for movement to downwardly inclined position upon engagement with a ball rolled on said floor, means for locking said slide against movement in one direction, the movement of said slide in one direction a predetermined distance, moving all of said pins to downwardly inclined position, one of said pins upon 25 movement to downwardly inclined position effecting a release of said locking means; means, operable at will, for preventing a movement of said slide in said direction, upon release of said locking means, a sufficient distance to move said pins to downwardly inclined position; and means for 30 moving said slide in the other direction, the movement of said slide in the other direction effecting a movement of said pins to upwardly projected position. 35

In testimony whereof I have signed the foregoing specification.

FOREST A. ROCKWELL.
